UNITED STATES PATENT OFFICE.

JOSEPH MERRITT, OF HARTFORD, CONNECTICUT.

LINK.

1,161,004.

Specification of Letters Patent. Patented Nov. 16, 1915.

Application filed April 12, 1915. Serial No. 20,626.

To all whom it may concern:

Be it known that I, JOSEPH MERRITT, a citizen of the United States, residing at Hartford, in the county of Hartford and State of Connecticut, have invented a new and useful Improvement in Links, of which the following is a specification.

This invention relates to those endless links of circular, oblong, or other shape, used in the jewelry, plumbing, hardware and furniture arts for articulating parts together, which are made up of a tubular sheath, usually formed of a precious metal, as gold, or a relatively soft metal, as copper, and a core generally formed of a baser metal, as brass, or a stronger metal, as steel.

The object of the invention is to produce a link of this character which is very easily manufactured and is very strong when completed, the strengthening core being so shaped that it will readily and surely pass into, conform to and fill the interior without distorting or disfiguring the sheath, and will interlock its ends in such manner that when the sheath is closed into final shape the ends of the sheath are so closely united and so firmly held by the core that they cannot be separated even if not fastened by solder or sweating.

In the accompanying drawings Figure 1 shows a section of a sheath and a side view of a core therefor, before being put together. Fig. 2 shows a similar view with the ends of the core started into the sheath. Fig. 3 shows the same with the core pushed farther into the sheath. Fig. 4 shows the core still farther in. Fig. 5 shows the core almost all in and the sheath being closed together. Fig. 6 shows the core completely in and locked and the sheath closed into ring form. Fig. 7 shows on larger scale the method of interlocking the core ends by tongue and notch. Fig. 8 shows the notch in one core leg. Fig. 9 shows the tongue in the other core leg.

The tubular sheath 1, which forms the exterior of the link, may be made to any desired size and made of any suitable material. This sheath, which can be circular or have any other shape in cross section, is formed substantially U-shape with its ends 2 that are to abut when the link is completed curving toward each other. The core 3 is also made substantially U-shape of wire of a diameter that will just fill the opening in the sheath with which it is to be used. This

core is considerably longer than the sheath and the legs of the core are somewhat closer together than the legs of the sheath. The ends of the legs of the core are tapered so that when they are forced into the sheath they will overlap and completely fill the interior. In order to make sure that the ends of the core will pass each other when they are forced in and the sheath is closed into its final form the tapered portion of the leg 4 is curved outwardly and then its tip is bent inward, while the tapered portion of the leg 5 is bent outward and curved more gradually than the end of the other leg. Core legs of this form enter into and slide freely in the curved ends of the sheath without unduly straining or deforming the sheath. When the parts are forced together for closing the link the end of the leg 4 follows around the interior with its tip bearing against the inner wall of the sheathing, while the end of the leg 5 follows around with its tip closely hugging the outer wall of the sheathing. This eliminates any liability of interference with each other of the ends of the legs of the core and insures their passing each other so that they will properly wedge together in the interior of the sheath.

The tapering portion of the leg 4 is provided with a notch 6 on one side and the tapering portion of the leg 5 on the same side is provided with an inwardly struck tongue 7. When the core is forced into the sheath and the ends of the sheath are brought together so as to complete the link, which may be accomplished by a hand tool or in a machine, and the tapering portion of the legs of the core have passed each other so as to fill the sheath, the tongue on the one leg springs into the notch on the other leg and locks the legs together so that the core cannot be pulled apart without fracturing the structure.

These links may be completely formed by the manufacturer, or the sheathings and cores can be sold disassembled, to be assembled by the user. The sheathings for these links may be made of gold, silver, or other precious metal, or they may be made of brass, copper, or other base metal, depending upon the use to which they are to be put, and of course they may be made of any desired size and shape. The cores are desirably made of steel, or other suitable metal which will impart the requisite strength to

the link. These links are particularly serviceable when the sheaths are made of precious metal for uniting parts of chains and articles of jewelry, and when made larger and of heavier material they are suitable for securing handles and many other articles used in the hardware, plumbing and furniture trades which are commonly fastened by links.

10 The invention claimed is:

1. A link composed of a tubular sheath and a core, said core having its ends overlapped and interlocked within the tubular sheath.
- 15 2. A link composed of a tubular sheath and a solid core, said core having its ends tapered and overlapped, with the tapered and overlapped ends interlocked within the sheath.
- 20 3. A link formed of a tubular sheath and

a core, said core having a tongue on one leg interlocking within the sheath with a notch on the other leg.

4. A link formed of a tubular sheath and a core, said core having the ends of its legs beveled, and one having a notch and the other having a tongue, the beveled ends of the core overlapping and the tongue lying within the notch when the core occupies the sheath and the link is completely formed. 25

5. A tubular sheath approximately U-shape in form, and a core approximately U-shape in form and adapted to enter the sheath, with the ends of the legs of the core tapered and curved so they will pass each 30 other and overlap and fill the sheath when they are forced therein and the ends of the sheath are brought together. 35

JOSEPH MERRITT.
